COLLAPSIBLE CURTAIN HANGER

Sol Ruskin, Brooklyn, N. Y.

Application May 19, 1950, Serial No. 162,846

2 Claims. (Cl. 160—335)

1

The present invention relates to improvements in extensible supports or hangers for curtains or draperies in conjunction with casement windows, hospitals, beauty parlors and the like.

Draperies sometimes are supported by rings on fixed rods above the tops of casement windows and care must be taken to push them back well out of the way before the window is opened. In addition to supporting the curtains or draperies on fixed rods or rings, the curtains or draperies may be hung on rigid cranes which can be swung on vertical axes so as to permit free opening of the window, but such cranes are unsightly when swung into the room. In hangers of both kinds the movement of the draperies is effected by cords and pulleys, with the result that the curtain or drapery is apt to be bunched at one side and is not uniformly distributed especially when it is desired to move the curtain or drapery to an intermediate position.

The use of hanging means for curtains and draperies that are in the form of lazy tongs also has been proposed. This arrangement has been open to certain objections however, in that such type of hanging means is lacking in rigidity, and also has been open to the objection that it may become accidentally swung on the vertical axis while the curtain is in expanded position, resulting in possible damage to the curtain or dislocation thereof.

The present invention has for one of its objects the provision of certain improvements in a lazy-tongs type of hanger, whereby the hanger becomes locked in position automatically and responsively to its expansion into curtain-hanging position in its place of use, and released responsively to collapse of the hanger for enabling the collapsed hanger to be pivoted about a vertical axis for snugly engaging a wall or casement of a window or the like, whenever it may be desired for any reason to displace the hanger from its operative, expanded position, thereby enhancing the appearance of the hanger and enabling it to be moved into a completely unobstructed position relative to a wall or window.

A still further object of the invention is the provision of reinforcing means for the hanger, which means are mounted permanently on the hanger and permit unobstructed expansion and contraction thereof, the said reinforcing means being positioned intermediate the ends of the hanger when the said hanger is expanded, and which is adjusted as to length so that it will not extend beyond the ends of the hanger when the latter is collapsed, while at the same time

2

strengthening the hanger intermediate its length against tendencies to sag or buckle under the weight of a curtain or drapery carried by the hanger when the latter is expanded.

A still further object of the invention is to provide improved retaining mounting means for the ends of the hanger which are adapted to fit snugly against the frame or casement of a window or similar opening, for retaining in an efficient manner the expanded hanger in operative or expanded position relative to the said opening, while permitting ready release of the hanger for collapsing and swinging movements thereof.

Further objects of the invention will become apparent as the description proceeds, and the features of novelty will be pointed out in particularity in the appended claims.

The improved construction of the present invention will become more readily understood by reference to the accompanying drawings which illustrate one form or embodiment of the improved construction, and in which:

Fig. 1 represents a view of the hanger installed in operative position to extend across the top of a window, door, or similar opening, with a curtain or drapery carried on the hanger.

Fig. 2 is an enlarged side view of the improved hanger of the present construction partially expanded, showing certain details of construction thereof, parts of the construction being broken away.

Fig. 3 is a sectional view taken on the line III—III of Fig. 2 looking in the direction of the arrows.

Fig. 4 is a disassembled perspective view of the locking means for securing the improved device in expanded, operative position.

Referring more particularly to the drawings, a window or similar opening A is provided with the improved curtain hanger of the present invention, the opening A having the lateral vertical frame members 1 and 2, and the horizontal top member 2', which spans the vertical lateral members 1 and 2. The hanger is indicated generally at B in Fig. 1, and is indicated therein as being in expanded position and having a curtain or drapery C with its upper end folded thereover, concealing it from view, and being suspended therefrom. It will be understood that in this description and appended claims, the term "curtain" and "drapery" are used synonymously and interchangeably.

The improved hanger comprises toggle-arms 3 and 4, which define a lazy-tongs arrangement, the arms 3 and 4 being interconnected pivotally

at their extremities as indicated at 5 and 6, and also at their center cross points as indicated at 7. The pivotal connections include pivot pins 8 and spacer washers 9 interposed between the arms 3 and 4.

The terminals of the lazy-tongs assembly are mounted slidably on terminal posts 10 and 11 by means of slidable connecting brackets 12 and 12' which are pivotally connected to the lower extremities of the end lazy-tong arms, the top extremities of the said terminal arms being fixedly secured to the terminal posts 10 and 11 by brackets 13 and 14, respectively, and pins or bolts 16. The terminal post 10 is mounted by the fastening element 15 on the inner surface of the frame member 1 by screws or the like 17, said fastening element 15 being a flat metallic plate or strip that is secured to the inner surface of the frame member 1 by said screws or equivalent fastening means 17, and to the ends of the supporting terminal post 10 by bearing brackets or sockets 18 20 by screws 18'.

It has been noted above that the terminal brackets 12 and 12' are slidable on the terminal posts 10 and 11, respectively, whereas the top brackets 13 and 14 are fixedly secured to the said terminal posts. It will be understood, however, that the brackets 13 and 12 are rotatable relative to the terminal post 10, so that the hanger construction may be rotated around a vertical axis, namely, the terminal post 10 when the lazy-tongs with curtain C are normally in collapsed position as will be directly more clearly explained.

The locking instrumentalities mentioned above include a plate 20 mounted on the fastening strip or element 15 and secured by screws 20' and which is provided with a slot 21 having an open lower end 22, the rounded corners 23 of which form guides for a projecting tongue 24 of the lower terminal bracket 12 which slidably embraces the terminal post 10, the engagement of the tongue 24 in the slot 21 preventing pivotal turning of the hanger assembly relative to said terminal post 10 while the hanger assembly is expanded, the extension of the lazy-tong arms causing the tongue 24 of the bracket 12 to rise upwardly in the slot 21. The top bracket 13 is secured between the top bearing socket 18 and collar 25 secured to terminal post 10 by a set screw 26, and which maintains the upper edge of the lazy-tongs and curtain in the same horizontal plane whether collapsed or expanded, and causes locking tongue 24 to assume operative and inoperative positions by the movement of the lazy-tongs structure. When the lazy-tong arms 3 and 4 are collapsed, the tongue 24 slips out from the open end of the slot 21, thereby releasing the hanger assembly for turning on the post 10 so as to enable rotation of the hanger assembly from the window A, normally in collapsed position. It will be noted from Fig. 4 that the sliding bracket 12 is bifurcated, as indicated at 27, to receive the lower end 28 of the terminal lazy-tong arm 3, a pin 29 passing through registering openings 30 in the bifurcated end 27 of the bracket 12 and opening 31 in the end 28 of the arm 3, the said pin 29 forming a pivotal connection between the bracket 12 and the arm 3 of the lazy-tongs assembly.

The lazy-tongs assembly is braced by a bar 32 that is mounted intermediate the lazy-tong arms 3 and 4, as shown in Fig. 2. This bar 32 is provided with oppositely extending, open ended slots 33 and 34, which receive the slidable pivot pins 8 connecting the arms, there being a central web

35 intermediate the slots 33 and 34 which receives another of the pivot pins 8 and is secured thereby in permanently mounted relation relative to the lazy-tongs assembly. The slots 33 and 34 with their oppositely disposed open ends, permit the lazy-tong arms to be expanded and contracted freely while the central web permanently secures the bar 32 in place relative to the arms 3 and 4. The engagement of the slidable pins with the slots 33 and 34 reinforce and render rigid the hanger assembly when in extended position; and when the assembly is collapsed the bar 32 clears the end posts, the bar 32 being shorter than even the collapsed length of the hanger assembly.

With further reference to the curtain C it will be noted that said curtain is provided along one edge with a piping 19, extending from a point corresponding to the lower edge of the lazy-tongs structure B when in collapsed position, and through which is adapted to concealingly extend post member 11. Said post 11 is adapted to support the hanger B and curtain C, not only when fully expanded as shown in Fig. 1, but at any point within its expansive range, and, if desired, at any intermediate point within the rotative limits with respect to post 10 and frame element 1.

Said curtain or drapery C has its upper end folded or draped over the hanger B a distance sufficient to house and conceal said hanger, and secured by the separable snap fasteners 36 attached to the curtain proper and the folded portion 37 at points intermediate the arms 3 and 4, Fig. 1, so that said curtain will move with and remain in proper position with respect to the hanger and in proper draping arrangement in both hanger expanded and collapsed positions.

It will be further noted that the hanger structure B with its curtain C may be positioned at any desired point within its rotative limits about its supporting post 10, in addition to its right angular position with respect to anchor strip 15, when locking tongue 24 is moved out of register with slot 21, as will be well understood.

From the above it will be apparent that I have provided a curtain or drapery hanger device, including unique means automatically operable to hanger locking position by the expanding movement of the hanger, and automatically releasable upon movement of said hanger to collapsed position to permit rotative movement of said hanger about the axis of its supporting medium to a position removed from or off-set with respect to its operative position, said device being simple in construction and operation, manufacturable at a nominal cost, and efficient for the purposes intended.

It is thought that the operation of the construction will be obvious from the foregoing description, and that further reference thereto is unnecessary; and while the accompanying drawings illustrate a preferred embodiment of the improved construction of this invention, it will be apparent that various structural details may be subject to modification without departing from the inventive concept. Accordingly, it will be understood that it is intended and desired to embrace within the scope of the present invention such modifications and changes as may be necessary to adapt it to varying conditions and uses, as defined by the appended claims.

What is claimed is:

1. A curtain hanger comprising, in combination, means for supporting a curtain in a window opening and including a supporting medium and a plurality of toggle arms, means pivotally inter-

connecting the toggle arms at opposite extremities thereof, pivotal means interconnecting mid-portions of the arms, the said arms thereby defining a lazy-tongs assembly, terminal posts interconnected to the assembly at the opposite extremities of adjacent terminal arms of the said assembly, one of the terminal posts being a fixed short post restricted to upper portions of the window opening, means for mounting the said short terminal post and lazy-tongs assembly in said window opening, the terminal arms of the said assembly being pivotally connected to their adjacent terminal posts by upper and lower connecting brackets, means for restraining said upper brackets against longitudinal movement along their terminal posts, the lower pivotally mounted brackets being slidably longitudinally along said posts responsive to opening and closing movements between the said arms of the lazy-tongs assembly, and means for locking the said assembly against rotation around the fixed terminal post, the said locking means including a slotted plate mounted on said supporting medium adjacent to the said terminal post, and a complemental tongue member projecting from the slidable bracket into the slot in the said slotted plate, the said slot and tongue restraining the lazy-tong assembly when fully extended against rotary movement around the said fixedly mounted terminal post while permitting free expansion and contraction between the said arms of the lazy-tongs assembly, and brace means mounted on the said assembly for stiffening the said assembly against sagging under weight of a curtain on the said assembly, the other of the terminal posts being mounted in lateral piping on the curtain and extending to and supported by the floor, and being freely movable with the curtain into and out of engagement with the window opening around the fixedly mounted terminal post as a vertical axis of rotation, with the lazy-tongs assembly in selected extended and collapsed position.

2. A curtain hanger comprising, in combination, means for supporting a curtain at a window opening or the like, and including a plurality of toggle arms pivotally interconnected at both extremities and medially thereof to define a lazy-tongs assembly, mounting means laterally disposed on a window frame for mounting the said assembly in position relative to the window opening, terminal members pivotally secured to the lazy-tongs assembly coacting with the

mounting means for holding the assembly in expanded position across the window while enabling rotary movement of the assembly relative to the window incident to contraction thereof, and means cooperating with the mounting means and at least one of the terminal members for locking the lazy-tongs assembly against rotary movement responsive to expansion of the said assembly, the locking means including a locking member slidably mounted on the said terminal member and slidably movable thereon responsive to opening and contracting movements of the said assembly, a locking tongue extending laterally from the locking member, and a locking plate fixedly mounted on the window frame and provided with a longitudinally extending slot adapted to receive the said locking tongue of the slidably mounted locking member in locking engagement with the sides of the slot responsive to opening movement of the said assembly and to release the locking member responsive to closing movement of the said arms of the lazy-tongs assembly, the said slot having an open lower end defining guide surfaces for guiding the locking tongue into the slot, opening movement of the said assembly causing a lifting of the slidably locking member until the locking tongue thereon enters the slot, the said slot having a closed upper end defining a stop for the tongue for limiting opening movement of the said assembly and engagement of the locking tongue with the sides of the slot preventing pivotal rotation of the assembly when in open position, the locking member and its tongue moving downwardly responsively to closing movement of the said assembly until the said locking tongue clears the slot when the said assembly is substantially closed, thereby releasing the said assembly for pivotal movement around the mounting means.
